UNITED STATES PATENT OFFICE.

SYLVESTER B. LEIDY, OF PHILADELPHIA, PENNSYLVANIA, ASSIGNOR TO THE ENTERPRISE MANUFACTURING COMPANY OF PENNSYLVANIA, OF SAME PLACE.

COLLAPSIBLE SCREW-THREADING TAP.

SPECIFICATION forming part of Letters Patent No. 662,861, dated November 20, 1900.

Application filed April 25, 1900. Serial No. 14,329. (No model.)

To all whom it may concern:

Be it known that I, SYLVESTER B. LEIDY, a citizen of the United States, residing in Philadelphia, Pennsylvania, have invented 5 certain Improvements in Collapsible Screw- Threading Taps, of which the following is a specification.

The object of my invention is to construct a tap for cutting internal threads, so that after the article is threaded the cutters of the tap can be retracted to allow the tap to be immediately withdrawn from the article or the article moved away from the tap.

In the accompanying drawings, Figure 1 is 15 an inverted plan view of my improved collapsible tap. Fig. 2 is an end view. Fig. 3 is a longitudinal sectional view showing the cutters projected. Fig. 4 is a view similar to Fig. 3, showing the cutters retracted. Figs. 5, 20 6, and 7 are perspective views illustrating details of the invention, and Fig. 8 is a diagram view illustrating the action of the trigger.

A is the body of the tap, having a shank a arranged to be coupled to any suitable tapping-machine. The body is hollow, and mounted in the hollow body is a plunger B, having 25 a tapered head b, which projects the cutters and holds them in the projected position during the tapping operation.

Pivoted to the body A at care three or more 30 levers C. Carried by each lever is a cutter D, of the form clearly illustrated in Fig. 5. This cutter has the teeth, as shown, and a beveled rear edge, which is preferably on the same bevel as the head b of the plunger B. The cutter is secured to the lever C by a confining-screw d, and in order to prevent it from turning on the lever the cutter has a channel d', into which projects a portion c' of the lever C, 35 so that the strain is taken off the bolt d. Each lever C has a rear projection c', and arranged in a socket a' in the body A is a spring e. This spring is arranged in a thimble a' in the body, and carried by the spring is a head e', which 40 bears against the under side of the arm c' of the lever C. The springs tend to force the cutters toward the center and in contact with the tapered head b of the plunger B, so that as soon as the plunger is withdrawn the springs 45 retract the cutters.

A' is a collar secured to the end of the body A by means of a screw α^3 . This collar prevents springing of the head, which is cut away to allow for the free movement of the levers C.

Arranged to slide on the body A is a sleeve F. This sleeve has a threaded portion f, and on the threaded portion are the screw-collars E E.

B' is a pin extending through the plunger B and also through slots g g in the body A and through slots f' in the sleeve. The pin B' extends into the space between the collars E, so that on adjusting these collars on the threaded portion of the sleeve F the position 60 of the sleeve F in respect to the plunger B can be altered, so as to adjust the plunger in respect to the cutters.

Mounted within the body A is a spring G, which is secured to a pin g' at the rear end 70 and to the plunger B at its forward end. This spring tends to retract the plunger and also to retract the sleeve F, to which it is connected.

Pivoted to sleeve F at i is a trigger I, having two arms i' i'', the arm i' being undercut at i''.

h is a spring bearing against the arm i' of the trigger I, so as to keep the trigger in the position illustrated in Fig. 1.

Bearing against the end of the arm i' of the trigger I is a pusher J, Fig. 8, attached to the 80 machine to which the tap is secured, and the trigger is released from the pusher when the arm i'' strikes a stop K on the fixed portion of the machine, so that as soon as the trigger is released the sleeve F is released from the control of the pusher and the spring G withdraws the plunger and its sleeve and allows the cutters to be reciprocated, so that by setting the stop K at any point a thread can be cut of any desired length. When the pusher J returns, the spring h forces the arm i' of the trigger I again in front of the pusher, so that its plunger B can be moved forward to project the cutters when it is desired to cut another thread.

Thus it will be seen that I am enabled to provide a substantial collapsible tap which will cut the threads accurately and quickly and of any length desired within the limit of the tool, and the tap can be adjusted to any 90 95 100

automatic tool which has a given motion and to which the articles to be threaded are fed to the tapping mechanism by automatic means.

I claim as my invention—

5. 1. The combination of the body, pivoted levers, cutters carried thereby, a plunger having a head acting to project the cutters, a spring tending to retract the plunger, a sleeve coupled to the plunger, and mechanism on the sleeve actuated by operating mechanism on the machine to force the plunger forward to project the cutters, substantially as described.
15. 2. The combination of the body, cutters carried thereby, a plunger arranged to project the cutters, a spring for retracting the plunger, a sleeve on the shank connected to the plunger, and means for adjusting the sleeve in respect to the plunger, substantially as described.
25. 3. The combination of a body, cutters carried thereby, a plunger having a head acting to project the cutters, a sleeve, a pin carried by the plunger and projecting through slots in the body and in the sleeve, said sleeve being threaded, threaded rings mounted in the threaded portion of the sleeve and between which the pin projects, so that on turning the rings the plunger can be adjusted, substantially as described.
30. 4. The combination of a body, movable cutters, a plunger for projecting the cutters, a sleeve connected to the plunger, a trigger pivoted to the sleeve and having two arms, a pusher and a stop, one arm of the trigger receiving the thrust of the pusher, and the other arranged to come in contact with the stop and trip the trigger so as to free it from the pusher, substantially as described.
40. 5. The combination of a body, cutters carried by the body, a plunger within the body arranged to project the cutters, a sleeve connected to the plunger, a trigger pivoted to the sleeve having two arms, one of said arms being undercut, a pusher and a stop, the undercut arm of the trigger taking the thrust of the pusher, a spring tending to keep the arm in line with the pusher, the other arm being in line with the stop, whereby it is tripped so as to withdraw the trigger from the pusher, substantially as described.
45. 6. The combination in a collapsible tap, of a body having a collar integral therewith, levers pivoted in recesses in said collar, cutters on said levers, a plunger within the body having a head acting to project the cutters and to hold them in the projected position, and a loose sleeve on the outside of the shaft operatively and adjustably connected to said plunger, substantially as described.
55. In testimony whereof I have signed my name to this specification in the presence of two subscribing witnesses.
60. SYLVESTER B. LEIDY.
